UNITED STATES PATENT OFFICE

CLIFFORD W. SKOGH, OF CHICAGO, ILLINOIS, ASSIGNOR TO MAGILL-WEINSHEIMER COMPANY, OF CHICAGO, ILLINOIS, A CORPORATION OF ILLINOIS

PRICE MARKER FOR GOODS

Application filed July 31, 1929. Serial No. 382,360.

My invention relates to a price marker for goods and particularly to a marker which is adaptable for display with a package of goods. One object is the provision of such a marker which may be inserted in the package or in the interstices between the units housed in the package. Another object is the provision of such a price marker in which means are provided for varying the price marking. Other objects will appear from time to time in the course of the specification and claims.

I illustrate my invention more or less diagrammatically in the accompanying drawings, wherein—

Figure 1 is a front elevation of one form of my device;

Figure 2 is a section on the line 2—2 of Figure 1;

Figure 3 illustrates the blank outstretched;

Figure 4 is a rear view of the marker;

Figure 5 is a section on the line 5—5 of Figure 1;

Figure 6 is a front elevation of a variant form of my device;

Figure 7 is a rear view of the device shown in Figure 6;

Figure 8 is a section on the line 8—8 of Figure 6;

Figure 9 is a front elevation of a further variation of the device;

Figure 10 is a rear elevation of the form of Figure 9; and

Figure 11 is a section on the line 11—11 of Figure 9.

Like parts are indicated by like characters throughout the specification and drawings.

Referring to the form of Figures 1 to 5 A generally indicates a box or container in which may be positioned the articles A¹, such as cakes, soap and the like.

B generally indicates the body portion of the price marker element. It may include a display or advertising surface B¹ and one or more apertures B².

Adapted to be folded to the rear of the apertured portion is the flap C which may be secured to the member B as by the indented line or folding connection C¹. It may be apertured as at C² for ease in han-

dling the symbols later described. In forming and printing the blank a plurality of removable symbols D may be associated with the flap C in such fashion as to be detachable or removable therefrom. In the article as assembled ready for use the flap C is folded in the position in which it is shown in Figure 4 and may be secured for example by the wire securing members C³. The device may be shipped with the detachable members D still detachably secured to the flap C, for removal by the operator at the time of use.

In order to permit the insertion of the marker in the goods I provide side flaps E, E¹, foldably mounted upon the opposite edges of the member B and provided with downwardly extending portions E² which extend below the plane of the line or junction C¹, when the device is in the assembled position of Figure 4. These downwardly extending flaps E² may then be inserted between adjacent articles A¹, as shown in Figures 1 and 2. Preferably each such marker will be proportioned to the size of the units being dispensed in the package used.

In the alternative form of my device shown in Figures 6 to 8 inclusive I dispense with the side flaps E, E¹ with their lower extensions E² and merely insert the lower edge of the bowed portion B between adjacent articles or between an article and the container, as shown in Figure 8.

In the form of Figures 9 to 11 inclusive I form the flap C with a side flap or extension G which is adapted to be folded into position at right angles to the plane of the body portion B. When in such position, or at any other sufficient angle, it serves as a rear support or base, whereby the marker may be placed on any flat surface, for example the top of a box or container.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic

rather than as limiting me to my specific showing.

The use and operation of my invention are as follows:

5 I find it desirable in dispensing various articles, for example soap, to have a marker which may be positioned upon or in the top of a container filled with soap. As the preferred example of my device I provide the 10 form of Figures 1 to 5, wherein the tabs or flaps E² may be inserted between adjacent cakes of soap, as shown in Figure 1. The marker itself may be employed with various 15 grades of soap or may be varied in accordance with changes in price, as for example when a sale or reduction in price is advertised. I do not wish to be limited to any particular size, number or relationship of apertures, but I find it useful to employ one aperture to indicate the number of cakes and another aperture to indicate the price. To the rear of the 20 aperture the operator may position the necessary digits, removing the removable digits D from the flap C and employing whichever ones are necessary. The remainder may be 25 kept, for example, for changes in price, etc. The digits may be slid laterally into the space between the flap C and the body portion B and the apertures B² and C², which give 30 access to the fingers of the operator, add to the ease of this lateral insertion.

In the form of Figures 6 to 8 inclusive I dispense with the special tabs E² and merely insert the article as a whole between adjacent cakes of soap or between a cake of soap and the wall of the box. In the form of Figures 9 to 11 inclusive I employ the flap G which virtually makes an easel of the marker.

The digits may be coated at the rear side 40 with any suitable adhesive substance to enable the user to stick or fasten them to the marker.

I claim:

1. A blank for price signs, formed of a 45 fibrous material, such as paper, which includes a main portion and a second portion adapted to be folded in relation to the main portion, the main portion being apertured in line with the second portion when the second portion is folded, and a plurality of detachable portions having indicating symbols thereon, the detachable portions being of such a size and the symbols being so positioned thereon as to align the symbols with 50 said apertures when the detachable portions are positioned between the main and the second portions with their lower edges engaging the fold between said main and second portions.

2. A blank for price signs, formed of a 60 fibrous material, such as paper, which includes a main portion and a second portion adapted to be folded in relation to the main portion, the main portion being apertured in 65 line with the second portion when the second

portion is folded, and a plurality of detachable portions having indicating symbols thereon, the detachable portions being of such a size and the symbol being so positioned thereon as to align the symbols with 70 said apertures when the detachable portions are positioned between the main and the second portions with their lower edges engaging the fold between said main and second portions, said second portion being also 75 apertured in line with said detachable portions, when the detachable portions are in indicating position.

3: A blank for price signs, formed of a 80 fibrous material, such as paper, which includes a main portion and a second portion adapted to be folded in relation to the main portion, the main portion being apertured in line with the second portion when the second portion is folded, and a plurality of detachable portions having indicating symbols thereon, the detachable portions being of such a size and the symbols being so positioned thereon as to align the symbols with 85 said apertures when the detachable portions are positioned between the main and the second portions with their lower edges engaging the fold between said main and second portions, said detachable portions being initially formed as part of said second portion. 90

4. A blank for price signs, formed of a 95 fibrous material, such as paper, which includes a main portion and a second portion adapted to be folded in relation to the main portion, the main portion being apertured 100 in line with the second portion when the second portion is folded, and a plurality of detachable portions having indicating symbols thereon, the detachable portions being of such a size and the symbols being so positioned thereon as to align the symbols with 105 said apertures when the detachable portions are positioned between the main and the second portions with their lower edges engaging the fold between said main and second portions, and additional portions, in 110 foldable relationship with said main portion, including end edges depending beneath the fold between the main and second portions when the second portion is folded. 115

5. A blank for price signs, formed of a 120 fibrous material, such as paper, which includes a main portion and a second portion adapted to be folded in relation to the main portion, the main portion being apertured 125 in line with the second portion when the second portion is folded, and a plurality of detachable portions having indicating symbols thereon, the detachable portions being of such a size and the symbols being so positioned thereon as to align the symbols with 130 said apertures when the detachable portions are positioned between the main and the second portions with their lower edges engaging the fold between said main and sec- 135

ond portions, and means, associated with said blank, for supporting it in upright position when the second portion is in folded relationship with the main portion.

6. A blank for price signs, formed of a fibrous material, such as paper, which includes a main portion and a second portion adapted to be folded in relation to the main portion, the main portion being apertured in line with the second portion when the second portion is folded, and a plurality of detachable portions having indicating symbols thereon, the detachable portions being of such a size and the symbols being so positioned thereon as to align the symbols with said apertures when the detachable portions are positioned between the main and the second portions with their lower edges engaging the fold between said main and second portions, and a foldable bracket positioned upon said blank.

Signed at Chicago, county of Cook and State of Illinois, this 25th day of July 1929.

CLIFFORD W. SKOGH.
